(57) **CLAIM**

The ornamental design for an erotic article, as shown and described.

DESCRIPTION

FIG. 1 is a front perspective view of one embodiment of an erotic article in accordance with the present design;

FIG. 2 is a front elevational view thereof;

FIG. 3 is a rear elevational view thereof;

FIG. 4 is a top plan view thereof;

FIG. 5 is a right side elevational view thereof;

FIG. 6 is a left side elevational view thereof;

FIG. 7 is a front perspective view of an alternative embodiment in accordance with the present design of FIG. 1;

FIG. 8 is a front elevational view of the alternative embodiment illustrated in FIG. 7;

FIG. 9 is a rear elevational view of the alternative embodiment illustrated in FIG. 7;

FIG. 10 is a top plan view of the alternative embodiment illustrated in FIG. 7;

FIG. 11 is a right side elevational view of the alternative embodiment illustrated in FIG. 7; and,

FIG. 12 is a left side elevational view of the alternative embodiment illustrated in FIG. 7.

The stippling in the drawings is for shading purposes only.
